UNITED STATES PATENT OFFICE.

FRANK B. BIGELOW, OF DETROIT, MICHIGAN, ASSIGNOR TO MURPHY IRON WORKS, OF DETROIT, MICHIGAN, A CORPORATION OF MICHIGAN.

ARCH-PLATE.

1,026,645.

Specification of Letters Patent.

Patented May 14, 1912.

Application filed October 1, 1910. Serial No. 584,822.

To all whom it may concern:

Be it known that I, FRANK B. BIGELOW, a citizen of the United States of America, residing at Detroit, in the county of Wayne and State of Michigan, have invented certain new and useful Improvements in Arch-Plates, of which the following is a specification, reference being had therein to the accompanying drawings.

10 This invention relates to an arch plate for furnaces and more particularly to an arch plate adapted to form one wall of the coal magazine of an automatic stoker.

15 The object of this invention is to provide an arch plate for the purpose so constructed that the lower end thereof which is exposed to extreme heat in the furnace and liable to become cracked, warped or burned out, may be quickly and easily renewed without tearing down or in any way disturbing the arch or any other part of the furnace, said portion of the arch plate being renewable through the coal magazine.

20 A further object of the invention is to provide certain other new and useful features in the construction and arrangement of parts, all as hereinafter more fully described and particularly pointed out in the claims reference being had to the accompanying drawings in which,

25 Figure 1 is a perspective detail of a portion of an automatic stoker showing an arch plate in place therein embodying the invention; Fig. 2 is a transverse vertical section 30 through such furnace; Fig. 3 is a perspective detail of a portion of the arch plate showing the same in section and some of the detachable sections removed; Fig. 4 is a transverse vertical section through the arch 35 plate; and Fig. 5 is a perspective view of one of the detachable sections.

40 For the purpose of illustration the arch plate is shown embodied in a particular construction of automatic stoker, but it is obvious that it may be adapted for use in any furnace having a coal magazine.

45 As shown in Figs. 1 and 2, 1 are inclined grate bars supported at their lower ends upon a grate bearer 2 with their upper ends resting against coking plates 3 over which coal from magazines 4 above, is shoved by the stoker boxes 5 actuated by segments on rock shafts 6, all constructed and arranged

as in the common and well known forms of automatic stokers.

55 The inner side of each of the coal magazines 4 is formed by an arch plate 7 embodying this invention. This arch plate comprises a casting 8 extending the full length of the furnace and it is formed with laterally extending inclined portions 9 and 10 forming skew seats for arches 11 and 12 which spring over the fire chamber from the coal magazine extending along one side of the furnace to the magazine at the other side, with a space 13 between the arches. This arch seat casting is strengthened by vertical ribs or webs 14 at intervals throughout its length, and a horizontal rib 15 extending inward from the wall of the casting a short distance below the arch seat 9. The wall of the casting is also formed with a series of openings 16 below the rib 15 and between the webs 14, said openings forming outlets for the air from the space 13 between the arches. The upper straight vertical portion 17 of the casting 8 forms part of a vertical side wall for the magazine 4 and this vertical wall for the magazine is completed by a series of detachable sections or plates 18 which engage the inner edges of the webs 14 at their ends and are formed with a laterally extending angular lower end 19 extending beneath the arch seat 10 and forming the upper side of the discharge throat of the magazine. These several sections are securely and detachably held in place by a stud 20 on each of the ribs 14 to engage notches 21 in the ends of the plates and each plate intermediate its ends is formed with a hole to receive a bolt 22 which is screwthreaded at its inner end to engage a screwthreaded opening 23 in the wall of the casting 8.

85 The upper edge of each section is held in place by its engagement with a groove in the main casting 8, formed by a projecting rib 27 thereon. Each of the sections 18 is spaced at its lower end from the lower end of the casting 8 by a series of spaced ribs or webs 24 cast integral with the inclined lower end 19 and extending upward a short distance on the vertical wall of the section. These ribs 24 extend beyond the inner edge of the arch seat 10 and the first course of 90 bricks or blocks 25 of the arch 12 are formed

to extend downward over the edge of the arch seat and engage the ends of the ribs 24. These ribs thus form between them together with the webs 14, a series of air passages 5 26 communicating at their upper ends through the openings 16 with the space between the arches 11 and 12 and opening at their inner ends along the inner lower edge of the lower arch directly above the coking 10 plate. The inner edge of the arch seat 10 is thus protected by the fire brick of the arch and the circulation of air through the air 15 passages prevents said seat from being warped or burned out by extreme heat. 15 Each section 18 is secured intermediate its ends to the arch-seat member by a single bolt and is held at its edges by the studs 20 and ribs 27. Said sections are therefore 20 free to expand and contract independently 25 of each other and of the arch-seat member, and all warping or cracking of the parts due to unequal expansion or contraction is prevented.

When the protecting ends of the detachable sections which extend beneath the lower arch seat become burned out by the extreme heat, any one of these sections may be quickly and easily detached and removed and a new one put in its place, as access may 30 be had to the bolts 22 through the coal magazine and the plates may be detached and removed through said magazine without disturbing the arches or any other part of the furnace. It is obvious that the protecting 35 portion of the arch plate may be made in one piece, but in that event it could not be as readily removed through the magazine, and it is therefore preferably made in detachable sections.

40 Having thus fully described my invention what I claim is:

1. The combination of a coal magazine having an arch seat member forming one side thereof and provided with a seat for 45 an arch, an arch engaging said seat, a removable protecting member having a portion forming a vertical side wall of the magazine and a portion extending outwardly beneath the said arch seat, said protecting 50 member being spaced from said arch seat to form an air passage between them, and means on the arch seat member for attaching the protecting member thereto and permitting a movement thereof relative to the 55 arch seat member upon expansion or contraction of said members.

2. The combination of a coal magazine having an arch seat member formed with laterally extending arch seat portions 60 spaced apart and connected by a wall, arches engaging said seat portions, a removable protecting member formed with a portion forming a plane side wall of the magazine and a portion extending laterally beneath 65 the lower arch seat, said protecting member

being spaced from said arch seats and their connecting wall to form an air passage between them and said member, and means for detachably attaching said protecting member to the arch seat member.

70

3. The combination of a coal magazine having an arch seat member forming one side thereof and provided with a seat for an arch, an arch engaging said seat, a series of protecting members having portions extending beneath the arch seat and portions 75 extending upwardly within the magazine to form a portion of a side wall thereof, said upwardly extending portions being provided with notches in their ends, and studs on the 80 arch seat member to engage the notches and support said members.

75

4. An arch plate adapted to form one side of a coal magazine, comprising a member formed with an arch seat at one side and 85 provided with openings above said seat, and a member detachably attached to the other side of said seat member extending beneath said seat and spaced from said member to form an air passage communicating with 90 the space above said arch seat through said openings.

90

5. An arch plate adapted to form one side of a coal magazine, comprising a member formed with an arch seat at one side, and a member detachably attached to the other side of said seat member extending beneath said seat and formed with a series of ribs 95 for spacing said member from said seat member and forming a series of air passages 100 between said members extending beneath the arch seat.

95

6. An arch plate comprising a member formed with a vertical wall adapted to form a wall of a coal magazine and with an arch seat at one side near its lower edge, a protecting member forming a continuation of the wall of said member, having a portion extending beneath said seat and forming the upper wall of the discharge throat of said 105 magazine, and means for detachably securing said protecting member to said seat member with a space between said members.

105

7. An arch plate comprising a seat member formed with a vertical wall adapted to 115 form a portion of one wall of a coal magazine and with a portion extending laterally from the lower end of said wall forming a seat for an arch, a protecting member formed with a vertical wall forming a continuation of the wall of said seat member and with a portion extending laterally from the lower end of its wall projecting beneath the arch seat of said seat member, means for spacing said members forming a series of 120 air passages between, and means for detachably securing said protecting member to said seat member.

115

8. An arch plate comprising a member formed with a vertical wall adapted to form 130

120

125

130

one wall of a coal magazine and with a laterally extending portion forming a seat for an arch, and a series of protecting members detachably secured to said members beneath the said seat and separately removable through the magazine.

9. An arch plate comprising an arch supporting member formed with a vertical wall and a portion extending laterally from the lower edge of said wall formed with upper and lower spaced arch seats and openings between said seats, a plurality of detachable members each formed with a vertical wall and with a portion extending laterally from the lower end of said wall beneath the lower arch seat, ribs on the laterally extending portion of each detachable member for spacing said members from said supporting member and forming a series of air passages beneath the lower arch seat, said series of openings in said supporting member forming inlets for said passages, and means for detachably securing said detachable members to said supporting member.

25 10. An arch plate comprising a member formed with a vertical wall, a portion extending laterally from the lower end of said wall and forming a skew seat for an arch, a connecting wall extending downward from the edge of said seat, a portion extending laterally from the lower end of

said connecting wall and forming a skew seat for a lower arch, and vertical webs projecting from the lower surfaces of said portions forming the arch seats and said connecting wall; a series of detachable members each formed with a vertical wall and a portion extending laterally from the lower end of said wall beneath the lower arch seat, said members engaging the edges of said webs; and means on said webs for engaging and holding said detachable members.

11. An arch plate comprising a member formed with a laterally extending portion along its lower edge forming a continuous arch seat, an arch engaging said seat and a protecting member detachably secured thereto and extending beneath said seat, said protecting member being formed with a series of parallel ribs engaging the lower side of said laterally extending portion and extending beyond the edge thereof to engage bricks of the arch seated upon said seat and form a series of air passages between said members.

In testimony whereof I affix my signature in presence of two witnesses.
